UNITED STATES PATENT OFFICE

AUGUST P. BJORREGAARD, OF OKMULGEE, OKLAHOMA

PROCESS OF REFINING OIL

No Drawing.

Application filed August 26, 1925. Serial No. 52,683.

One of the present day standard requirements in the gasoline trade is that gasoline offered for sale shall be non-reactive or "sweet" to the sodium plumbite or "doctor" test. As is well known, moreover, gasoline from the still is refined usually by treatment first with sulfuric acid and then either by treatment with litharge and sodium hydroxide or with sodium hypochlorite, the treatment with litharge and sodium hydroxide or with hypochlorite being necessary to render the gasoline "sweet" to the "doctor" test.

It is the custom at present, moreover, at many retail gasoline or filling stations to exhibit to the customer the product being sold by using filling bowls of glass. It has developed that many gasolines refined so as to pass the "doctor" and other ordinary trade tests are light sensitive, causing the gasoline to turn darker in the glass filling bowls on standing therein and also depositing a film of dark gum that collects on the glass, thus doubly darkening the tint of the gasoline as viewed by the purchaser.

According to the present invention, straight-run and cracked gasoline or mixtures of straight-run and cracked gasolines are refined to produce a gasoline which is "sweet" to the "doctor" test, non-corrosive, of good odor and light stable. The term "light stable" as just used is intended to include both the characteristics of not substantially darkening and of not depositing gum upon exposure to light.

When gasoline is refined according to the present invention, most of the previously known chemicals for treating processes are not required. In fact, some of them are detrimental if combined with the present process. In refining gasoline according to the present invention, a little normal or primary alcohol is added to the "sour" gasoline preferably in the raw or untreated state, which is then treated with a hydroxide of alkali metal or of alkali earth of heavier atomic weight than calcium until "sweet" to the "doctor" test. The gasoline will then be found to be light stable and of good odor requiring no further treatment.

The primary alcohols used according to the present invention are active in inverse proportion to their molecular weight. Tests have been made with methyl, ethyl, normal propyl, normal butyl, and higher normal or primary alcohols. Methyl alcohol acts quickly; ethyl alcohol acts somewhat slowly; whereas normal propyl, normal butyl and higher normal or primary alcohols act more slowly and still more slowly. A methyl alcohol suitable for use in the present process is pure wood alcohol, approximately 100% test, and substantially free from acetone. I have been successful in rendering gasolines, both "sweet" to the "doctor" test and light stable when using as little as $\frac{1}{10}$ of 1% by volume of methyl alcohol to gasoline treated. The amount of alcohol necessary when using a given primary alcohol and a given gasoline can be readily determined by a routine test prior to commercial operation. The presence of acetone in the alcohol used according to the present process does not prevent the resulting gasoline from being "sweet", but it is not completely light stable. It is, however, improved as to its characteristics toward light in that while it goes off color slowly it does so without production of cloud or gum. Acetone by itself without alcohol is not effective in making gasoline either "sweet" to the "doctor" test or completely light stable.

None of the secondary alcohols, if used instead of methyl or other primary alcohol in the present process, makes the gasoline finally and fully "sweet" to the "doctor" test, even after twenty-four hours action. They, however, favorably affect the gasoline as to its reaction when exposed to light, the color of the gasoline after light exposure being less intense if it has been first treated with secondary alcohol and caustic soda or equivalent hydroxide. The secondary alcohols, however, develop a strong yellow tone in the gasoline if attempted to be used according to the present invention.

The alkaline material or hydroxide used along with or subsequent to the treatment of the gasoline with normal alcohol according to the present invention may be either potas-

sium, sodium, lithium, barium or strontium hydroxide. However, lithium, barium and strontium hydroxides must remain in contact with the alcohol treated gasoline a longer time than potassium or sodium hydroxide to make it "sweet." Commercially, caustic soda is the most available alkaline substance for use according to the present invention. It may be added to the gasoline preferably in a powdered state after or along with the treatment with the alcohol with agitation of the caustic and gasoline till "sweet" to the "doctor" test. The preferable method, however, is to percolate the alcohol treated gasoline through a mass of granulated caustic soda until "sweet" to the "doctor" test. A sirupy solution of caustic soda or caustic potash in pure methyl alcohol may be used instead of treatment first with the alcohol and then with the hydroxide, but a dilute solution is not operative. As little as 0.2 lb. of powdered caustic soda per barrel of gasoline is often effective in producing a "sweet" light stable gasoline according to the present invention. The amount of caustic or other hydroxide required in treating gasoline according to the present invention varies with the gasoline and the hydroxide and may be determined readily for any given gasoline and a given hydroxide by a routine test preliminary to commercial operation.

The use of normal alcohol alone without subsequent treatment with hydroxide does not produce the desired result. The same is true of treatment with caustic alone without treatment with normal alcohol.

The gasoline to be treated by the present process must be substantially free from water throughout the process in order to obtain the desired results. Moreover, the gasoline used must be unsweetened. If the gasoline has been sweetened by either the sodium plumbite or sodium hypochlorite treatment, subsequent treatment according to the present invention is not effective in producing a light stable gasoline.

Acid treatment with 66° Beaumé sulfuric acid may be applied before the treatment according to the present process without detriment but it is not necessary. Acid treatment with 60° Beaumé sulfuric acid however is detrimental either before or after treatment of the gasoline according to the present process, and especially detrimental after it.

The process of refining gasoline according to the present invention is applicable to gasolines direct from the still without any redistillation. In fact, the major portion of the experimental work done on the present invention has been on a blend of distillates direct from the pressure still and direct from the crude still.

Gasoline treated by the process of the present invention is of greatly improved odor and needs no further treatment to improve

its odor for sale. As to color, the process of the present invention does not change the original color of the gasoline.

It will be understood that wherever the phase "caustic alkali hydroxide" or "alkali hydroxide" is used in the following claims, hydroxides of the heavy earth metals, barium and strontium, are intended to be included.

It will be understood further that the alcohol referred to in the claims as "high-test" alcohol may contain some acetone. The acetone is effective along with the alcohol in preventing gum formation as described above and comes within the contemplated scope of the present invention.

Having thus described my invention, I claim:

1. A process of treating gasoline comprising removing water from the gasoline, mixing with the dry gasoline a high test alcohol, mixing the alcohol-gasoline mixture with a dry caustic alkali hydroxide, and separating the alcohol-gasoline mixture from the alkali hydroxide.

2. A process of treating gasoline comprising mixing less than one per cent of substantially dry methyl alcohol with the gasoline, treating the mixture with a caustic alkali hydroxide, and separating the mixture from the alkali hydroxide.

3. A process of treating gasoline comprising mixing a small amount of the methyl alcohol with the gasoline, and passing the gasoline-alcohol mixture through a bed of powdered caustic hydroxide.

4. A process of treating gasoline comprising removing water from the gasoline, mixing substantially pure methyl alcohol with the dry gasoline, and passing the gasoline-alcohol mixture through a bed of powdered sodium hydroxide.

5. A process for refining gasoline comprising mixing a dry normal alcohol with substantially dry raw gasoline, contacting the resulting alcohol-gasoline mixture with a dry powdered alkali hydroxide, and separating the alcohol-gasoline mixture from the alkali hydroxide.

6. The process of treating gasoline comprising forming a mixture of substantially dry gasoline with less than 1% of its volume of substantially dry alcohol, contacting the mixture with dry alkali hydroxide, and separating the mixture from the alkali hydroxide.

7. The process of treating gasoline to render it light stable, which comprises forming a solution of dry unsweetened gasoline with a relatively small proportion of dry primary alcohol, contacting the resulting gasoline-alcohol solution with an alkali hydroxide, and separating the gasoline-alcohol solution from the alkali hydroxide.

8. The process of treating "sour" gasolines, which comprises forming a mixture of substantially dry gasoline with a relatively small

proportion of substantial dry primary alcohol, contacting the resulting mixture with a substantially dry alkali hydroxide, and separating the said mixture from the alkali hydroxide.

- 5 9. The process of treating "sour" gasolines, which comprises contacting the gasoline with concentrated sulphuric acid, thereafter forming a mixture of the gasoline with a small proportion of substantially dry primary alcohol, contacting the resulting mixture with a substantially dry alkali hydroxide, and separating the said mixture from the alkali hydroxide.
- 10
- 15 In testimony whereof I affix my signature.

AUGUST P. BJERREGAARD.
